UNITED STATES PATENT OFFICE.

GEORGE D. DEMETROPOULOS, OF NEW YORK, N. Y.

AMUSEMENT DEVICE.

1,369,887.

Specification of Letters Patent.

Patented Mar. 1, 1921.

Application filed February 2, 1920. Serial No. 355,553.

To all whom it may concern:

Be it known that I, GEORGE D. DEMETROPOULOS, a citizen of the United States, residing at New York, in the county of New York and State of New York, have invented new and useful Improvements in Amusement Devices, of which the following is a specification.

This invention relates to amusement devices.

Some of the objects of the invention are; to produce a device of the character mentioned with which individuals upon the payment of a nominal fee may compete with each other in a "submarine race" which will involve skill as well as luck to be returned the winner; another object of the invention is to arrange buoyant bodies on submerged tiltable tracks—there being one buoyant body for each track and these tracks are tilted to cause the bodies to submerge and inasmuch as these bodies are buoyant, they will, under the action of the water, have a natural tendency to rise to the surface and in their endeavor to rise to the surface, they will be compelled to travel along their respective tracks upon which they are arranged for movement and to which they are connected, use being made of anti-friction rollers to facilitate the travel of the buoyant bodies; another object of the invention is to produce a device as characterized which embodies track tilting means so that in a case where a plurality of tracks and buoyant bodies are in use, these tracks may be actuated singly in the first instance, and unison in the second instance, that is to say, each individual competing shall have to do with his or her own particular track and buoyant body which body, in the present instance, is a miniature submarine, whereas the proprietor or conductor of the race has to do with and takes charge of, the return of all of the submarines to their normal starting positions, hence the single and simultaneous actuation of the tiltable tracks.

In the drawing:

Figure 1 is a sectional elevation of the device embodying the present invention.

Fig. 2 is a transverse sectional view taken on the line 2—2 of Fig. 1.

Fig. 3 is a transverse sectional view taken on the line 3—3 of Fig. 1 and looking into the direction as indicated by the arrow.

Referring now to the drawing, it will be seen, that use is made of a tank 10 which

contains a suitable amount of water. Arranged within the tank 10 and submerged below the surface of the water is a tiltable means 11. This tiltable means comprises a track or tracks 12 which are supported by arched members 13 which are pivotally mounted in bearings 14 secured to the bottom of the tank 10. In order that the tracks 12 may be tilted there is provided tilting means which in the present instance consists of loop members 15 which are correlated one to each of the tracks 12 and connected to the upper end of each loop member 15 there is a flexible element 16 which may be trained over suitable pulleys 17 to bring the end of the members 16 within reach of an individual competing in the game. Correlated to the ends of the track 12, opposite to the ends to which the loop members 15 are correlated, is a member 18 which has connected to the upper end thereof a flexible member 19 which is trained over suitable pulleys 20 to bring the end thereof within reach of the proprietor or conductor of the device so that he may cause the simultaneous movement of the tracks 12. Arranged for movement on each of the tracks 12 is a buoyant boat-like body 21 in the nature of a miniature submarine. Each of these submarines is correlated with its respective track by the use of a plurality of members 22 which support anti-friction rollers 23, the rollers being movable along the opposite edges of the track.

In practice, the submarines 21 are disposed—all of them—at one end of the tank 10 upon the elevated ends of the tracks 12. The signal to start is then given, when each individual competing pulls on the flexible member 16 thereby causing the end X of the track to which the same is correlated by the loop member 15 to opposite end Y of the track to lower, thereby causing the submarine 21 to submerge and under action of the water and inasmuch as the submarine is a buoyant body, the same to be caused as it tries to rise to the surface of the water to move along the track 12 this being true as regards each of the other submarines 21 in the race and the first submarine to reach the finishing point will be returned the winner. Certain indicating mechanism may be employed to indicate the winner of the race and said indicating mechanism may be actuated by the impact of the movable submarine inasmuch as they will be of consider-

able weight and movable in a tank of considerable size. By virtue of the pull member and the member 19 the elevation of the ends Y of the tracks 12, and the lowering of the 5 ends X thereof may be effected in unison, with the result that the submarines 21 will be returned to their starting points. The side of the tank 10 arranged nearest the competing individuals may embody a glass panel 10 so that such individuals may view the submarines as they progress along the courses.

It is to be understood that no limitation is necessarily made to the precise showing herein made, but that changes and modifications within the scope of the claims may be resorted to when desired.

What is claimed as new is:—

1. A device as characterized comprising a tank having water therein, means including a tilttable track submerged in the water in said tank, and a buoyant body arranged for movement on the track.

2. A device as characterized comprising a tank having water therein, means including a plurality of tilttable tracks submerged in the water in said tank, and a buoyant body arranged for movement on each of said tracks.

3. A device as characterized comprising a tank having water therein, submerged

tiltable tracks, a buoyant boat-like body arranged for movement on each of said tracks, and tilting means in correlation with said tracks for tilting the same.

4. A device as characterized comprising a tank having water therein, submerged tilttable tracks, a buoyant boat-like body arranged for movement on each of said tracks, and tilting means in correlation with said tracks for effecting the lowering of certain 40 ends of the tracks singly.

5. A device as characterized comprising a tank having water therein, submerged tilttable tracks, a buoyant boat-like body arranged for movement on each of said tracks, 45 and tilting means in correlation with said tracks for effecting the lowering of certain ends of the tracks in unison.

6. A device as characterized comprising a tank having water therein, tilttable means 50 including a plurality of tracks which are submerged in the water in said tank, a buoyant body arranged for movement on each of said tracks, means for raising certain ends of the tracks singly, and means for raising certain other ends of the tracks simultaneously.

In testimony whereof I have affixed my signature.

GEORGE D. DEMETROPOULOS.
